POWER WRENCH FOR WELL TUBING
AND RODS

Carlton W. Dawson, Taft, Calif.

Application July 11, 1933, Serial No. 679,921

13 Claims. (CL 255—35)

The present invention relates to power operated wrenches especially adapted for unscrewing and screwing up the joints of well tubing and sucker rod springs.

5 The principal object of the invention is to provide an apparatus of the described type which is easy and quick to use, and which can be operated by one man, thus saving both time and labor in the customarily tedious operation of 10 pulling and replacing the tubing and sucker rod strings in deep wells. Other objects of the invention are to provide readily interchangeable jaws of chucks for gripping different sizes of 15 pipes and rods; to provide a movable chuck carrying head which can be applied to and removed 20 from the tubing without moving the main body and motor of the machine; and to provide for the adequate and rigid support of said main body.

25 The invention is herein illustrated and described as embodied in a machine for rotating the tubing and sucker rod sections of a deep well for the purpose of screwing up and unscrewing the joints thereof. It will be apparent, however, that the machine, if constructed of suitable size, may be used for rotating well casing sections, or for any other purpose for which a power wrench is useful. It should be understood, moreover, that the form, construction and arrangement of the several parts may be varied, within 30 the limits of the claims hereto appended, without departing from the spirit of the invention as set forth therein.

35 Reference will be made to the accompanying drawings, wherein:

Fig. 1 is a vertical part sectional view of a preferred embodiment of the invention as applied to the casing head and tubing string of a well.

40 Fig. 2 is a horizontal section of the head, taken on the line 2—2 of Fig. 1.

Fig. 3 is a transverse sectional detail of the chuck, taken on the line 3 of Fig. 2 and enlarged.

45 Fig. 4 is a part sectional elevation of the head as applied to a sucker rod string.

Fig. 5 is a horizontal section on the line 5—5 of Fig. 4.

50 Fig. 6 is a perspective view of the complete machine.

Fig. 7 is a side elevation of a portion of the machine, showing the clutch operating lever.

In its preferred form, the machine comprises a main frame of carriage 11 provided with wheels 12 adapted to rest movably upon the derrick

floor, and a swinging head 13 which carries the jaws for gripping the well tubing or sucker rods. Any suitable means may be used for anchoring the carriage 11, either to the casing head or to the derrick floor. For example, I have shown a 5 forked clamp 14 extending from one end of the carriage and adapted to embrace the projecting head of the well casing 15, said clamp having set screws 16 by which it is rigidly secured to said casing. At the rear end of the machine is an extension 17 which may be secured to the floor by a bolt.

The carriage 11 supports an electric motor 18 and a gear and clutch housing 19. The horizontal motor shaft 20, Fig. 1, enters the rear end 10 of said housing and has a pinion 21 fixed upon it, which meshes with an idler gear 22. A bevel pinion 23, secured to said idler, drives a bevel gear 24 secured upon a vertical shaft 25. A pinion 26 on said shaft 25 drives a larger gear 27 upon a second vertical shaft 28. A smaller gear 29 is also secured upon said shaft 28. The gears 27 and 29 mesh respectively with gears 30 and 31, both of which are independently rotatable upon a third vertical shaft 32, which is the driven 15 shaft of the gear set. The gear 30 is secured to one member 33 of a friction cone clutch, the other member 34 thereof being slidable upon the shaft 32, but prevented from rotating thereon by a transverse pin or key 35. The lower face of 20 the sliding clutch member 34 is provided with dogs or jaws 36, which engage similar jaws 37 on the gear 31. Thus when the clutch member 34 is moved downwardly, the gear 31 is clutched to the shaft 32, and said shaft is driven, at a 25 comparatively low speed, by the gears 29 and 31. When said clutch member is moved upwardly, the gear 30 is clutched to the shaft 32, which is then driven at a higher speed by the gears 27 and 30.

30 The clutch member 34 is shifted by a rod 38, secured to the transverse key 35 and extending downwardly through the center of the shaft 32. At the bottom of said rod is a thrust collar 39 connected with an arm 40 secured upon a rock 45 shaft 41, which extends to the side of the housing and is provided with a second arm 42, Fig. 7, connected by a link 43 with an operating lever 44. Thus by moving said lever, the driven shaft 32 may be started and stopped, and operated at 50 two different speeds. Reversal of said shaft is accomplished by reversing the driving motor 18.

The shaft 32 extends upwardly through the top of the housing 19, and drives the wrench jaw mounted within the head 13, as shown in Fig. 1. 55

A tubular arm 45 extends upwardly from said housing, and is connected therewith by a hinge joint 46. Within said arm is an extension 47 of the shaft 32, having two universal joints 48 and 5 a slip joint 49. The arm 45 is also made with a slip joint 50, its two telescoping portions being prevented from turning upon each other by splines 51. The head 13 is secured to the upper portion of the arm 45, and its weight is approximately balanced by a helical spring 52.

The upper end 53 of the shaft extension 47 is journaled in the head 13, and has a gear 54 secured upon it, which drives two trains of idler pinions 55, Fig. 2. The outer end portion of said head 15 13 carries a rotatable chuck carrier 56, Figs. 1 and 2, in the form of a partial ring having a center aperture 57 and a radial slot 58 leading outwardly therefrom to its periphery, said aperture and slot being wide enough to slip over or 20 around the largest tubing for which the machine is designed. The chuck carrier 56 is journaled in the head 13 by means of circular grooves 59 in its upper and lower faces which engage corresponding flanges formed upon the inside of the 25 head. The carrier 56 is provided with peripheral gear teeth, which mesh with the endmost idler pinions 55, said idlers being spaced apart sufficiently to span the gap 58 in the carrier gear, so that one idler is always in mesh therewith. 30 The outer end of the head is provided with a swinging gate or guard 60, which may be opened to permit it to pass around the tubing. It will thus be seen that the chuck carrier 56, which is 35 rotated by the extension shaft 47, is firmly journaled in the head 13, and positively driven by the gears 54 and 55, even though it is not a complete circle, but has a gap in it to allow it to be slipped over the tubing string from the side.

The upper face of the carrier 56 is recessed to 40 receive a chuck 61, which is prevented from rotating in said carrier by splines 62, Figs. 2 and 3. The upper plate of the head 13 is apertured to permit said chuck to be removed and replaced readily. Several different chucks are provided, 45 all having the same exterior dimensions to make them interchangeable in the carrier 56. Each chuck is provided with a radial slot 63 aligned with the slot 58 in the carrier. The center portions of the chucks are formed to fit and grip 50 whatever object is to be rotated. In Figs. 2 and 3 is shown a chuck adapted for gripping the well tubing 64, said chuck having a pair of toothed wedge jaws 65 slidably mounted upon undercut inclined guides 66, Fig. 3, and pressed inwardly by springs 67, thus forming an automatic pipe gripping chuck. The chuck 61 is reversible, i. e. it can be placed either side up in the carrier 56 according to the direction of gripping desired. Another form of chuck, for gripping squared 60 sucker rods, is shown at 61' in Fig. 5, having merely a rectangular central aperture 68 of suitable size to grip the squared portion of the sucker rod 69.

In operating the device, for instance in pulling 65 the tubing string from a well, the tubing 64 is pulled up by the usual elevator and tackle, until a joint 70, Fig. 1, rises above the casing head. Tapered slips 71 are employed to hold the tubing string by gripping its second section at the casing head, in the usual manner. The carriage 70 75 is then brought up, and anchored to the floor or casing head, or both, as circumstances may require. The swinging arm 45, carrying the head 13 with the proper chuck 61 therein, is then moved upwardly and said head and chuck are slipped

around the first tubing section, above the joint 70 to be unscrewed. The motor is started and by proper manipulation of the clutch lever 44 the upper tubing section is unscrewed, slowly at first and then faster when the threads become loosened. When the joint is unscrewed, the head 13 and arm 45 are swung back out of the way, the carriage 11 remaining in place, and the tubing string is again raised to the next joint.

In unscrewing the sucker rods, shown at 69 in 10 Fig. 4, the operation is the same, except that a wrench 72 of common form is used to hold the lower rod section. This wrench can be held in any suitable manner, as for example by a chain 15 73 attached to the head 13.

It will be seen from the foregoing that the machine can be operated quickly and easily by one man. The carriage 11, upon which the heavy parts are mounted, need not be moved until the entire pulling job is finished, the head 13 being 20 merely swung into and out of operative position at each joint of tubing. The slip joints 49 and 50 in the extension shaft and arm enable the head to rise or descend with the rotating tubing section. The chuck is engaged with and disengaged 25 from the tubing merely by the act of moving the head into and out of operative position, the only gate being the simple swinging guard 60 which can be opened and shut quickly and easily. By providing two spaced pinions 55 for driving the 30 slotted chuck carrier 56, assuring the meshing of at least one pinion therewith at all times. I eliminate the necessity for a complicated and troublesome gate to complete the peripheral gear of said carrier.

I claim:—

1. A power wrench comprising a frame; a hollow arm connected therewith for movement into and out of operating position; a head mounted directly upon and wholly supported by said arm; 40 a work engaging chuck rotatably mounted in said head; a motor mounted on said frame; and a shaft journaled within said arm for transmitting power from said motor to said chuck.

2. A power wrench comprising a frame; a hollow arm movably connected therewith; means for anchoring said frame; a work engaging chuck rotatably mounted on the upper end of said arm and wholly supported thereby; a shaft journaled within said arm for rotating said chuck; and 50 means mounted upon said frame for driving said shaft.

3. A power wrench comprising a frame; a hollow arm connected therewith for movement into and out of operating position; a head carried by the upper ends of said arm and wholly supported thereby; a work engaging chuck rotatably mounted in said head; variable speed gearing mounted on said frame; a shaft journaled within said arm for transmitting power from said gearing to said 60 chuck; and power means for driving said gearing.

4. A power wrench for well tubing comprising a carriage adapted to rest upon the derrick floor in proximity to the casing head; means for anchoring said carriage; a swinging arm rising from said carriage, said arm being movable toward and away from the well tubing; a rotatable chuck carried by said arm for engagement with said tubing; power means mounted on said carriage; and an articulated shaft journaled in said arm 70 connecting said power means with said chuck.

5. A power wrench for well tubing comprising a carriage adapted to rest upon the derrick floor in proximity to the casing head; means for anchoring said carriage; a movable arm secured to 75

- and rising from said carriage; a rotatable chuck carried by said arm, said arm being mounted for movement upon said carriage to carry said chuck into and out of engagement with the well tubing, 5 and said arm being extensible and retractible to enable said chuck to move up and down with said tubing; power means mounted on said carriage; and an articulated shaft journaled in said arm connecting said power means with said chuck.
- 10 6. A power wrench for well tubing comprising a carriage adapted to rest upon the derrick floor in proximity to the casing head; means for anchoring said carriage; a tubular telescoping non-rotatable arm having its lower end pivoted to 15 said carriage for movement toward and away from the well tubing; a rotatable chuck carried by the upper end of said arm for engagement with said tubing; power means mounted on said carriage; and an articulated shaft journaled in said 20 arm connecting said power means with said chuck.
7. A power wrench comprising a frame; power means mounted thereon; a jointed movable arm extending therefrom; a head carried by said 25 arm, said head having a slot therein; a rotatable chuck in said head, said chuck having a central work engaging aperture and a slot extending outwardly therefrom to its periphery, the slot in said chuck corresponding with the slot in said head 30 at one point in the rotation of said chuck; a partial gear carried by said chuck, said gear being interrupted at said slot; a pair of pinions in said head meshing with said gear and spaced apart to bridge said slot; a driving gear meshing with said pinions; and a shaft journaled in 35 said arm for connecting said power means and said driving gear.
8. A power wrench comprising a frame; an up-standing extensible arm connected therewith; a head mounted directly upon the upper end of 40 said arm and wholly supported thereby; a work engaging chuck rotatably mounted in said head; a spring associated with said arm for partially supporting the weight of said head and chuck; 45 and means for rotating said chuck.
9. A power wrench comprising a frame; an up-standing arm pivotally connected therewith for swinging movement in a vertical plane into and out of operative position; a work engaging chuck 50 rotatably carried by said arm; and means for rotating said chuck.
10. A power wrench comprising a frame; an extensible upstanding arm pivotally connected therewith for swinging movement in a vertical plane; a rotatable work engaging chuck carried by said arm; an articulated extensible shaft carried by said arm for rotating said chuck; and means mounted upon said frame for driving said shaft.
11. A power wrench for pipes, rods and the like comprising a rotatable chuck carrier having 10 a central aperture and a slot extending outwardly therefrom to its periphery; a chuck removably mounted in said carrier and provided with a slot aligned with the slot in said carrier; jaws mounted in said chuck for gripping the work in one 15 rotative direction, said chuck being bodily invertible in said carrier to enable it to grip and turn the work in either direction; and means for rotating said carrier in either direction.
12. A power wrench for pipes, rods and the like comprising a rotatable chuck carrier having 20 a recessed upper face, a central aperture, and a slot extending outwardly therefrom to its periphery; a chuck removably seated in the recess 25 of said carrier, said chuck having a slot aligned with the carrier slot; interengaging means upon said carrier and said chuck to prevent relative rotation; jaws mounted in said chuck for gripping the work in one rotative direction, said chuck being bodily invertible in said carrier to 30 enable it to grip and turn the work in either direction; and means for rotating said carrier in either direction.
13. A power wrench for pipes, rods and the like comprising a head having spaced horizontal 35 plates; a chuck carrier between said plates, the adjacent faces of said carrier and said plates being provided with annular interengaging guide means whereby said carrier is rotatably mounted in said head; a chuck mounted upon said carrier, said chuck, said carrier, and said head being provided with aligned central work receiving 40 apertures and slots leading outwardly therefrom; peripheral gear teeth formed upon said carrier, said gear being interrupted at said slot; a pair 45 of pinions mounted in said head and engaging the carrier gear, said pinions being spaced apart to bridge said slot, whereby one pinion is always in engagement with said gear; and power means for rotating said pinions.

CARLTON W. DAWSON
